UNITED STATES PATENT OFFICE.

FREDERICK T. ELLITHORPE, OF CHICAGO, ILLINOIS.

DESIGN FOR A GAME-INDICATOR CASE.

51,587.

Specification for Design.

Patented Dec. 18, 1917.

Application filed October 11, 1917. Serial No. 196,080. Term of patent 14 years.

To all whom it may concern:

Be it known that I, FREDERICK T. ELLITHORPE, a citizen of the United States, residing at 1700 Greenleaf avenue, in the city of Chicago, county of Cook, and State of Illinois, have invented a new, original, and ornamental Design for Game-Indicator Cases, of which the following is a specification, reference being had to the accompanying drawing, forming part thereof.

Fig. 2 is a side view of the same.

What I claim is:—

The ornamental design for a game indicator case as shown.

Signed at Chicago, county of Cook, State of Illinois, this 8th of October, 1917.

FREDERICK T. ELLITHORPE.
